UNITED STATES PATENT OFFICE.

DEXTER W. PARKER, OF MERIDEN, CONNECTICUT.

SUSPENSION DEVICE FOR LAMP-SHADES.

SPECIFICATION forming part of Letters Patent No. 311,519, dated February 3, 1885.

Application filed April 5, 1884. (No model.)

To all whom it may concern:

Be it known that I, DEXTER W. PARKER, a citizen of the United States, residing at Meriden, in the county of New Haven and State of Connecticut, have invented certain new and useful Improvements in Suspension Devices for Lamp-Shades, of which the following is a specification, reference being had therein to the accompanying drawings.

- 10 This invention relates to devices for holding the shades of hanging lamps, and more especially of the extension-lamps in common use. These lamps are sometimes provided with a crown-ring at the top of the shade, sometimes 15 with a base-ring at the bottom of the shade, and sometimes with both a crown-ring and a base-ring. In my present improvement I make use of both a crown-ring and a base-ring; but this is not by any means broadly new.
- 20 The shade has heretofore, in many instances, been suspended from the crown-ring. In many other instances it has been supported by the base-ring. In others it has been supported by hooks which depend from the crown-ring, or 25 directly by long chains from the canopy. Sometimes the harp has been attached to the crown-ring, and the latter has been attached to the chains, so as to become, after them, the primary means of suspension. Sometimes the 30 supporting-ring, whether base-ring or crown-ring, has been attached to the harp, and the latter used as a primary or intermediate means of suspending the shade. In my present improvement the shade-rings (crown and base) 35 are connected together by intermediate devices, so that the upper shade-ring or crown-ring sustains the weight of the lower shade-ring or base-ring, the suspension-chains being attached to the former. If the connections are rigid, the suspension-chains may be 40 attached to the base-ring instead. The weight of the shade may rest upon the base-ring; or the neck of the shade may be clamped to the crown-ring, so that it will be suspended therefrom.
- 45 In the accompanying drawings, Figure 1 represents a perspective view, taken from below, of an extension-lamp embodying my invention, the weight, canopy, and upper part 50 of the suspension-chains not being shown because having nothing to do with the invention. Fig. 2 represents a detail vertical sec-

tion of a shade, its rings, and their connections. Fig. 3 represents a similar view showing chains used as connections instead of rods. 55

In said drawings, A designates the suspending-chains of an extension-lamp fixture; B, the crown-ring; C, the shade; D, the base-ring; E, the lamp-harp, and F the lamp supported on that harp. The chains A are preferably, though not necessarily, three in number, arranged, as usual, at equal distances, and attached to the crown-ring B. The harp is attached to the base-ring by screws or in any convenient manner. 65

The shade C, as shown in Figs. 1 and 2, rests upon the base-ring; but, as shown in Fig. 3, it may be suspended from the crown-ring by means of clamping-screws e or other attaching devices. In this latter figure it does 70 not extend down to the bottom flange, d, of the base-ring, the latter being simply a protecting-ring.

In Figs. 1 and 2 the connecting devices between the crown-ring and the base-ring consist of rods E', which may be arranged either outside of the shade, as shown in Fig. 1, or inside thereof, as shown in Fig. 2. These rods should be adjustable and easily removable—the former to allow the use of shades 80 which vary in size, the latter to allow the fixture to be taken apart and the shade removed without difficulty. As shown in Fig. 2, I screw-thread the ends of the rods, pass them through openings in the horizontal flanges b d 85 of the shade-ring and crown-ring, respectively, and clamp them in place by nuts F. When the shade is attached to the crown-ring, as shown in Fig. 3, there is no need to make the connections adjustable, as a smaller size of 90 shade may be used without making any change in the fixture or in the relation of its parts to one another.

It is preferable to have the connecting devices inside the shade, as shown in Figs. 2 and 95 3, in order to facilitate the removal of the shade, and also to keep said connecting devices somewhat concealed.

In Fig. 3 chains are shown (marked G) as substitutes for rods E, the said chains being 100 provided with terminal hooks g, which are detachably hooked into openings in the flanges b d of the shade-rings.

It is obvious that many other devices for

attaching the rods or chains to the shade-rings may be employed instead of nuts and screw-threads or hooks.

I am aware that in a prior patent the suspension-chains are guided through openings in the crown-ring and attached to the base-ring; but this construction, though having some resemblance in appearance, is essentially different from mine. It does not really connect the shade-rings, and the crown-ring, with all the weight attached to it, bears upon the shade, which must always be in danger of fracture in consequence. My construction relieves the shade of this strain.

15 I am also aware that in earlier patents (notably in those taken out by myself either as sole inventor or jointly with others) the harp has been attached to both the upper shade-ring and the lower shade-ring, and might be 20 said to form a connection between them. The amount of material used in the harp when thus constructed is, however, very much greater than the amount required by the construction herein described, and the rods E or chains G 25 do not by any means make up the difference, these rods and chains being light and extending in a direct line without branches either from above or below. The result is greater cheapness in construction, and a reduction of 30 weight in the fixture as a whole. Again, the harp and lamp may be detached from the remainder of the fixture without disturbing the shade or reaching to the upper ring (crown-ring) thereof. This would be impracticable if 35 the harp were attached to both the crown-ring and the base-ring.

I am aware that an ornamental base-ring has sometimes been attached to a shade by screws and sometimes hung from the crown-ring by springs; but these methods are obviously unsuited to any base-rings except very light ones, and I make no claim to them in this application. The rods E' and chains G, being inextensible and inelastic, afford a secure 45 means of support for the heaviest base-ring. If springs were substituted, the momentum of the heavy base-ring would stretch them, and their resiliency would rattle the solid base-ring

against the shade, involving risk of fracture.

I am also aware that it is not new to employ 50 a crown-ring and a base-ring for securing in place a reflector or a globe, said rings being connected by rods detachably attached thereto.

I am also aware that it is not broadly new 55 to provide a crown-ring with hooks which support a lamp-shade, no base-ring being employed.

I do not claim either of these constructions; 60 but

What I do claim, and desire to secure by Letters Patent, is—

1. In an extension-lamp fixture, the combination of a crown-ring, a base-ring, a harp, and a shade with rods or chains which connect said rings to one another, substantially 65 as set forth.

2. In an extension-lamp fixture, the combination of a crown-ring, a base-ring, a harp attached to one of said rings, a lamp-shade, 70 and rods or chains which connect said rings to one another, substantially as set forth.

3. The combination of a crown-ring, a base-ring, and a shade with a lamp-harp suspended from said base-ring, and devices connecting said base-ring to said crown-ring, said connecting devices being independent of the harp, 75 substantially as set forth.

4. Adjustable connecting devices, in combination with two shade-rings, to which they 80 are attached, a shade arranged between said rings and supported by one or both of them, and a lamp harp attached to the lower ring and unattached to said connecting devices, substantially as set forth.

5. A lamp-shade and its crown-ring and base-ring, in combination with a harp attached to said base-ring, and connecting devices detachable from both of said rings, substantially 85 as set forth.

In testimony whereof I affix my signature in presence of two witnesses.

DEXTER W. PARKER.
